(21) Appl. No.: **29/143,144**

The ornamental design for a pair of over-boots with zipper and rear opening, as shown and described.

(22) Filed: **Jun. 8, 2001**

DESCRIPTION

(51) LOC (7) Cl. **02-04**

The nature and intended use of the article being an ornamental design to easily fit over shoe and foot in zipper at rear of boot. FIG. 1 is a front elevational view of the pair of over-boots with zipper and rear opening of the present invention;

(52) U.S. Cl. **D2/911**; D2/910; D2/909

FIG. 2 is a rear elevational view of the pair of over-boots with zipper and rear opening of FIG. 1;

(58) Field of Search .... D2/896-898, 900-903, D2/907-913, 920, 923, 943-960, 969, 970; 36/1, 1.5, 83, 114, 126-131, 7.1 R, 7.2-7.6, 8.1-11, 9 R, 10, 25 R, 45, 50.1, 77 R, 72 R

FIG. 3 is a left side elevational view of the pair of over-boots with zipper and rear opening of FIG. 1, the right view being a mirror image thereof;

FIG. 4 is a top plan view of the pair of over-boots with zipper and rear opening of FIG. 1; and,

FIG. 5 is a bottom plan view of the pair of over-boots with zipper and rear opening of FIG. 1.

The drawings attached hereto depict a right footed over-boot; the left footed boot is a mirror image thereof.
